UNITED STATES PATENT OFFICE.

LOUIS S. FLATAU, OF PITTSBURG, TEXAS.

BALING-PRESS.

SPECIFICATION forming part of Letters Patent No. 406,206, dated July 2, 1889.

Application filed December 14, 1888. Serial No. 293,615. (No model.)

To all whom it may concern:

Be it known that I, LOUIS S. FLATAU, of Pittsburgh, in the county of Camp and State of Texas, have invented a new and useful Improvement in Baling-Presses, of which the following is a specification.

My invention is an improvement in baling-presses; and it consists in the novel construction and combination of parts, as will be hereinafter described, and pointed out in the claim.

In the drawings, Figure 1 is a perspective view of my press. Fig. 2 is a vertical longitudinal section of the press-box. Fig. 3 is a cross-section of the press-box on line $\alpha\alpha$ of Fig. 2. Fig. 4 is a detail section illustrating the gearing. Fig. 5 is a detail view of the follower, partly broken away; and Fig. 6 is a detail view illustrating the connection of the screw-shaft with the ends of the follower.

The press-box A has baling-chambers B in its opposite ends, and in use is arranged horizontally, as shown. The walls of chambers B are formed with slots b, for the passage of the tying-wires, and are bound at their outer and inner ends by iron bands C and D, such bands encircling the chambers and giving great strength to the box. The removable doors E are fitted to the ends of the chambers and have flanges or edges e, which extend in position to be engaged by the bail-like clamps F, which have their arms hinged or pivoted at their free ends to the press-box, and are arranged to turn at their free or swinging ends over the edges of the doors and secure the same snugly in position. These doors have their inner edges formed with grooves for the tying-wire.

The plunger or follower G is formed with two plunger-blocks and a connecting-frame rigidly uniting such blocks, such frame consisting, preferably, of four beams H, fitting snugly in the corners of the press-box and rigidly connected at their ends to the end blocks, the follower being thus adapted to slide smoothly and evenly within the press-box and in both directions, as will be readily seen.

The screw-shaft I extends between the lower-blocks G and is connected to such parts. By preference I secure the screw-shaft rigidly

to such blocks, and by forming its ends i angular or otherwise non-circular in cross-section and fitting such ends in similar openings in plates J, secured to the inner sides of the blocks G. On this screw-shaft I, I fit a nut K, having gear-teeth, which are meshed by a gear l on the drive-shaft L. The nut K bears between one arm m of the bearing-frame M, which frame has arms m m', connected by cross-bar M', the said frame being secured to the press-box, the cross-bar M' providing a bearing for the drive-shaft L, and a distance sleeve or piece M² being provided between arm m' and the nut K, such construction enabling the placing of arms m m' sufficiently apart to permit the gear l to operate between them. The distance sleeve or piece M², it will be seen, is made integral with the arm m' of the bearing-frame M. On this piece M², I provide the stud or pin m², which forms a step or bearing for the lower or inner end of shaft L, steadies the operation of such shaft, and relieves the bearings of such shaft in frame M and in the box-frame of much of the wear and strain.

By the described construction it will be seen that by means of a sweep N, which may be the tongue of the machine detached from the hounds and attached to the drive-shaft, the gear l may be turned in one or the other direction to cause the follower to move toward one or the other end of the box. The hay or other material can consequently be placed in one chamber, the door of the same be fastened in position, and the screw operated to move the plunger-block with great force into such chamber. When the bale has been properly pressed, the wires may be applied and secured in the usual manner. After the bale has been secured the door may be opened and one or two turns given the sweep to force the bale out of the door. As a bale is being pressed in one chamber the hay or other material for another bale may be fed into the opposite chamber, the pressing of which would at once begin on the reverse movement of the sweep, thus saving time, as every movement backward or forward of the sweep is availed of to press in either one or the other chamber of the box.

In practice the press-box is usually sup-

ported on wheels, as shown, or on runners, to facilitate its passage from field to field, and when in use the machine may be staked in position in any desired manner.

5 Having thus described my invention, what I claim as new is—

In a baling-press, the combination of the press box or frame, the frame M, secured to said box or frame, and having an arm m , an 10 arm m' , and a distance-sleeve M^2 , extended from arm m' and provided with a pin or stud m^2 , the follower provided with a screw-shaft

extended through distance-sleeve M^2 and arm m , a bevel-gear K on said shaft between the sleeve M^2 and arm m , and the shaft L, 15 having a wheel l, meshing with the wheel K, such shaft L being journaled at its lower end on the pin or stud m^2 , all substantially as and for the purposes set forth.

LOUIS S. FLATAU.
